UNITED STATES PATENT OFFICE.

GEORGE A. JOHNSON, OF CHICAGO, ILLINOIS, ASSIGNOR TO WILLIAM H. MINER, OF CHAZY, NEW YORK.

REINFORCED END FOR BOX-CARS.

1,398,697.

Specification of Letters Patent. Patented Nov. 29, 1921.

Application filed April 3, 1919. Serial No. 287,236.

To all whom it may concern:

Be it known that I, GEORGE A. JOHNSON, a citizen of the United States, residing at Chicago, in the county of Cook and State of Illinois, have invented a certain new and useful Improvement in Reinforced Ends for Box-Cars, of which the following is a full, clear, concise, and exact description, reference being had to the accompanying drawings, forming a part of this specification.

10 This invention relates to improvements in reinforced ends for box cars.

As is well known, great difficulty has been experienced heretofore by the railroads in the operation of wood box cars due to the frequent breaking out or splintering of the end walls due to shifting of the load while the cars are in transit. Many thousands of wood box cars are in service representing a 20 great investment and many expedients have been employed to so reinforce the wood ends as to permit the continued use of the box cars in service.

The object of my invention is to provide 25 means for reinforcing the end walls of wood box cars so that a minimum expense to the railroads is involved and in such manner as to prevent or minimize the breaking out of said end walls.

30 More specifically, the object of my invention is to provide an extremely rigid and strong reinforcement in the form of a framework which may be applied to the outer sides of ends of wood box cars at small expense 35 and permit utilization of the inherent strength of the wood end walls.

In the drawings forming a part of this specification, Figure 1 is an elevational view of the end of a wood box car showing my 40 improvements in connection therewith. Fig. 2 is a horizontal, sectional view, partly broken away, taken on the line 2—2 of Fig. 1 upon an enlarged scale. Fig. 3 is a vertical, sectional view, partly broken away, 45 taken substantially on the line 3—3 of Fig. 1 and upon an enlarged scale. Fig. 4 is a horizontal, sectional view upon an enlarged scale, taken on the line 4—4 of Fig. 1. Fig. 5 is a perspective of one of the tie plates 50 employed with my construction.

In said drawings, the end wall of the box car is shown as formed with outer wood sheathing 10, vertical intermediate posts 11—11 and inner wood sheathing 12. The 55 car, of course, employs the usual corner

wood posts and diagonal bracing which need not be detailed. The end sill is shown at 13 in Fig. 3, the flooring at 14, the buffer block at 15, the end plate at 16, end fascia board at 17, roof at 18 and the foot boards 60 at 19.

In carrying out my invention, I preferably employ a pair of Z-bars indicated at 20—20, although it will be evident that other forms of commercially shaped beams may also be 65 employed. Two of such Z-bars 20 are preferably used, the same being applied to the outer face of the end wall in alinement with the intermediate posts 11 as shown in Fig. 4. Said Z-bars 20 extend to the bottom of 70 the end sill 13 and up to the end plate 16. At the top, the Z-bars 20 are rigidly tied together by a tie plate 21, the parts being preferably riveted as indicated at 22—22. Said tie plate 21 passes inside of the inner 75 flanges of the Z-bars and has its ends outwardly extended as indicated at 23 in Fig. 3, said ends being also riveted to the main webs of the Z-bars as indicated at 24. The plate 21 is bolted through to the end plate 80 16 in a number of places, as indicated in Figs. 1 and 3.

At the lower end of the Z-bars 20, a corresponding tie plate 25 is employed having outturned end flanges 26 riveted to the main 85 webs of the Z-bars as indicated at 27, the plate 25 being riveted also to the inner flanges of the Z-bars as indicated at 28. The lower tie plate 25 is bolted through to the end sill 13 as indicated in Fig. 3. 90

As will be obvious, the tie plates 21 and 25 space the Z-bars 20 from the outer wood sheathing 10 a distance corresponding to the thickness of the plates 21 and 25 and to fill this gap, I employ vertically extending flat 95 plates 29—29 as indicated most clearly in Fig. 4. The Z-bars and plates 29 are then bolted through the end wall and posts 11 by means of a series of bolts 30—30.

In order to better distribute the strains to 100 the superstructure of the car, I preferably employ a channel 31 extending crosswise of the car on the inner face of the end plate 16. Said channel 31 has the ends thereof bent at right angles along the inner faces of the 105 side walls of the car as indicated at 32. Said channel is bolted to the side walls of the car as indicated by the bolts 33 and near the corners of the car bolts 34 are employed passing through the end wall of the car. 110

Also, some of the bolts passing through the upper tie plate 21 are connected to the channel 31 as indicated in Fig. 3. At the corners of the car, I preferably employ reinforcing plates 35 as shown in Fig. 2 in order to obtain a better attachment for the bolts 33 and 34. In this way the corner structure of the car is very rigidly reinforced and the strains well distributed to the end and side walls of the car.

In carrying out my invention, it will be noted that I provide in effect, a rigid rectangular frame comprised of the Z-bars 20 and upper and lower tie plates 21. This frame may be fabricated in the shops and applied as a unit to the end wall of the car without modification of the latter and simply by making the necessary holes to accommodate the various securing bolts. The rectangular framework thus provided not only provides great strength against end thrusts imposed upon the end wall of the car but also provides great strength against spreading or lateral separation of the Z-bars. Furthermore, by employing the interior bracing in the form of the channel 31 at the top, the load is effectively distributed to the entire superstructure of the car thus adding increased strength to the end wall structure. All of the parts are such as are ordinarily found in stock in railroad repair shops and the improvements can be made at comparatively small expense to the railroads.

I claim:

1. In a box car having an end wall comprised of wood sheathing and posts, the combination with commercial shaped reinforcing beams secured to the outer side of said wall, of upper and lower tie plates rigidly secured to and connecting the upper and lower ends of said beams, said tie plates being interposed between the beams and the sheathing.

2. In a box car having an end wall comprised of outer wood sheathing and vertical posts, end plate and end sill, of vertically extending Z-bars alined with the intermediate end posts of the wall, an upper tie plate secured to the upper ends of the Z-bars and disposed between the Z-bars and the sheathing, an inner reinforcing member extending transversely of the car and disposed on the inner side of the end plate, the ends of said member being secured to the side walls of the car, securing means passing through said tie plate, end plate and member, a tie plate rigidly connected to the Z-bars at their lower ends in alinement with the end sill, securing means passing through said lower tie plate and end sill, said lower tie plate being also interposed between the Z-bars and the sheathing, and filler plates extending between the upper and lower tie plates and interposed between the Z-bars and the sheathing, said Z-bars and filler plates being additionally secured to the end wall of the car intermediate the tie plates.

3. In a box car having an end wall comprised of outer wood sheathing and vertical posts, a reinforcing structure on the outer side of the end wall, said reinforcing structure comprising, a pair of parallelly extending commercial shapes, upper and lower tie plates secured to the upper and lower ends respectively of said shapes on the inner sides thereof, and vertical filler plates disposed beneath said commercial shapes and extending between said tie plates, said tie plates and filler plates being interposed between the commercial shapes and the outer face of the sheathing.

In witness that I claim the foregoing I have hereunto subscribed my name this 29th day of March, 1919.

GEORGE A. JOHNSON.
